United States Patent Office

Des. 181,577
Patented Dec. 3, 1957

181,577

VALISE

Charles A. Breskin, Scarsdale, and Gerald E. Stahl,
Rye, N. Y.

Application September 27, 1956, Serial No. 43,112

Term of patent 14 years

(Cl. D87—5)

Fig. 1 is a front perspective view of a valise showing our new design;

Fig. 2 is an exploded end elevational view thereof showing the body and cover in separated position;

Fig. 3 is a front elevational view of the lower body portion as seen from the right of Fig. 2;

Fig. 4 is a rear elevational view thereof;

Fig. 5 is an end elevational view of the lower body portion as it appears with parts in extended position and the shelf cover thrown back;

Fig. 6 is a front elevational view of the lower body portion shown in Fig. 5; and

Fig. 7 is a top plan view thereof.

We claim:

The ornamental design for a valise, substantially as shown.
